UNITED STATES PATENT OFFICE.

WILLIAM H. HOWARD, OF CHICAGO, ILLINOIS.

DESIGN FOR A WRITING-DESK.

SPECIFICATION forming part of Design No. 37,080, dated August 9, 1904.

Application filed October 10, 1903. Serial No. 176,575. Term of patent 7 years.

To all whom it may concern:

Be it known that I, WILLIAM H. HOWARD, residing at Chicago, in the county of Cook and State of Illinois, have invented a new, original, and ornamental Design for Writing-Desks, of which the following is a specification, reference being had to the accompanying drawing, forming part thereof.

The drawing is a perspective of the new design.

What I claim as new, and desire to secure by Letters Patent, is—

The ornamental design for a writing-desk, as shown.

WILLIAM H. HOWARD.
